UNITED STATES PATENT OFFICE.

GEORGE N. GOODRICH, OF DETROIT, MICHIGAN.

RECORDING ATTACHMENT FOR PIANOS.

1,087,115.

Specification of Letters Patent. Patented Feb. 17, 1914.

Application filed September 30, 1912. Serial No. 723,008.

To all whom it may concern:

Be it known that I, GEORGE N. GOODRICH, a citizen of the United States, residing at Detroit, county of Wayne, State of Michigan, have invented a certain new and useful Improvement in Recording Attachments for Pianos, and declare the following to be a full, clear, and exact description of the same, such as will enable others skilled in the art 10 to which it pertains to make and use the same, reference being had to the accompanying drawings, which form a part of this specification.

This invention relates to apparatus for 15 producing indications on paper, that is to be perforated and used as a pattern, musical compositions that are being played upon a piano or other instrument. It is a recording attachment for pianos that mechanically 20 and accurately transfers the selection being played upon the pattern from which the perforated rolls are cut.

It has for its object, mechanism that performs three important offices; first, with 25 each stroke of the key, the printer is brought into contact with the sheet; second, provision is made to indicate the operation of the loud pedal in connection with the key struck; third, a device is provided for temporarily lifting the printer to indicate on 30 the sheet that a given key is being struck two or more times while the loud pedal is on.

In the drawings: Figure 1, is a diagrammatical view of the apparatus in the position of rest. Fig. 2, is a diagrammatical view of the apparatus in operation. Fig. 3 is a fragmentary view of the ribbon, showing the extended note-marks and also the interruptions in the extended note-marks.

40 A, is a portion of a piano or organ key below which is located a plunger 1 that reciprocates vertically in the guides 2 and 3. A coil spring 4 ordinarily keeps the plunger in its uppermost position by reason of 45 thrusting upward from the guide 3 against the collar 5 of the plunger 1. This plunger carries a contact 6 which is positioned with respect to the terminal 7 so as to rub that member at a given point in the descent of 50 the plunger. This terminal 7 comprises a

spring strip that is connected right-angularly with the bar 8 so as to form, in the whole, a bell-crank lever that is pivoted at 9. The bracket 10, which serves as a support for the pivoting 9, is metallic and is part of 55 the circuit that is traced from the guide 3 through the plunger 1, the contact 6, the terminal 7, and pivoting 9. This circuit continues through the wire 11 to the interrupter bar 12, that is pivoted at 13, thence through 60 the interrupter-bar terminal 14 to the stationary terminal 15, through the wire 16, the wire 17 to the contact 18. From the contact 18 the circuit continues through the loud-pedal lever 19, that is pivoted at 20, through 65 bracket 21, the wire 22, the battery S, the wire 23 to the coil 24 about the core 25. From the coil 24, the circuit leads back by the wire 26 to the guide 3 and is complete. It is, therefore, observable that, when the key 70 A is depressed, the contact 6 rubs with the terminal 7 after the key has been depressed some distance and completes the circuit already traced, thereby allowing a current to go through and energize the core 25. This 75 attracts the armature 27 that is carried on the printer-lever 28. This printer-lever is pivoted at 29 and ordinarily held out of contact with the master-strip P by the spring 30, but when the armature 27 is 80 attracted to the core 25, the printer-roll 31 is forced down in contact with the master-strip P that is passing across the printing block B. The master-strip P is pulled across this block at a uniform speed by the roll R 85 which is driven by a belt X. Devices for assuring a uniform draft upon the strip P regardless of the amount wound upon the roll may be provided, but as such are known and this is no part of my invention I have 90 not illustrated nor described one. As the strip is drawn across the block B and is contacted by the roll 31, a mark is left on the paper which may be later converted into a slot by cutting and the master strip used as 95 a pattern by which to cut the perforated sheets to be used on a piano playing machine. The marks printed on the master-strip will, when the same are transferred to the perforated sheets and run through a 100

piano playing machine, cause exact reproductions of the musical notes first played on the piano, organ or other musical instrument.

5 When the loud pedal is on, the sound of the note is extended through a longer time, and it is desirable that this prolongation be also recorded upon the sheet P. It is one of the features of my invention that mechanism to accurately secure such recording by 10 extending the note-mark is afforded. The extended note-marks are shown at 60 in Fig. 3. The mechanism to accomplish this comprises a shunt circuit 32 that leads from the 15 wire 16 to the wire 22, passing as a coil about the core 33. When this core 33 is energized it attracts the armature 34 on the bell-crank lever 7-8. Ordinarily this lever is held in the position shown in Fig. 1 by 20 the spiral spring 35. In this position of Fig. 1, it will be seen that the contact 6 does not engage with the terminal 7 until the plunger 1 has traveled some distance and disengages from this terminal 7 at an 25 early stage in the return travel. However, when the armature 34 is attracted by the core 33, the bell-crank lever 7-8 assumes the position shown in Fig. 2. The terminal 7 being a spring bar the contact 6 will have 30 a rubbing engagement with this terminal for the entire return stroke, thus resulting in the extension of the sound of the note being reproduced on the sheet P by lengthening the note marks until the loud pedal 35 is released or until the same key is tapped again as will be explained in the following paragraph.

The shunt circuit 32 is brought into operation by the depression of the loud pedal 36, which pushes up the link 37 and breaks the connection between the loud pedal lever 19 and the contact 18. (See Fig. 2.) The circuit can now be traced through the terminal 7, pivoting 9, bracket 10, wire 11, pivoting 13, interrupter bar 12, terminal 14, terminal 15, wire 16, shunt 32, wire 22, battery S, wire 23, coil 24, wire 26, guide 3, plunger 1 and contact 6. Very often, however, while the loud pedal is on, it is desired to tap the same key two or more times. This could not be done and make a showing upon the paper were it not that I have provided a special interrupter mechanism to cooperate with the apparatus described, so as 55 to make possible the recording of two or more taps of the same key while the loud pedal is on. This recording is accomplished by dividing the note-marks, see 61, Fig. 3. The mechanism to accomplish this comprises 60 a pawl 38 that is pivoted to the plunger 1 and which tends to thrust outward by reason of the coil spring 39. This thrust outward is counteracted by the pin 40 so that the pawl is guided in a given path and

will release the bar 12 when the shoulder 41 65 on the pawl has traveled a very short distance. The descent of the pawl with the plunger temporarily raises the interrupter bar against the pull of the spring 42 (dotted lines of Fig. 2) and separates the terminals 70 14 and 15, temporarily breaking the circuit through the interrupter bar and the wire 16. This occurs at every tap on the key and hence insures the distinct marking of the paper, while the loud pedal is pressed, each 75 time a tap is made on the key. The interrupter bar 12 is tripped at each depression of the key, but the tripping takes place before the contact 6 and terminal 7 engage. The inking roll 31 is fed with ink from a 80 trough 43 or any other conventional ink-feeding device. The spring 45 serves to keep the loud pedal member in engagement with the contact 18 when the player's foot is not upon the pedal 36. 85

The apparatus which I have described is (except for a few of the high keys) to be repeated for each key, except that, perhaps, some of it would not have to be repeated when the entire number of reproducers are 90 assembled into a complete apparatus for all the keys, as for instance, the battery S and the loud pedal 36 and the contact 18 and lever 19 could be made part of a return line common to all the circuits. The reproducer 95 could be used, of course, with pianos, organs, and other musical instruments and I do not wish to be understood as limiting myself to any specified type of musical instrument or any named automatic player of musical 100 compositions.

What I claim is:

1. The combination with a musical instrument, provided with keys and loud pedal, of a recording attachment comprising means for producing marks on the sheet of the roll upon the depression of the key, the said means including a printing member and means operated by the loud pedal for keeping the printing member in contact 110 with the sheet after the key is released, substantially as described.

2. The combination with a musical instrument, provided with keys and a loud pedal, of a recording attachment comprising means 115 for producing marks on the sheet of the roll upon the depression of the key, said means including a printing member, means operated by the loud pedal for keeping the printing member in contact with the sheet after 120 the key is released and means for temporarily lifting the printing member off the sheet of the roll when the key is tapped two or more times while the loud pedal is on, substantially as described.

3. A recording attachment for a piano, having in combination, a plunger adapted to be actuated by the key, a terminal arranged

to make an electrical connection with the plunger when the same has traveled some distance, a circuit closed by said electrical connection, a marker brought into operation by the closing of said circuit, and means operated by the loud pedal by which the position of the terminal is changed so as to hold the terminal in electrical connection with the plunger upon the return stroke of the plunger until the loud pedal is released, substantially as described.

4. A recording attachment for a piano, having in combination a plunger actuated by the key, a terminal arranged to form an electrical connection with the plunger when the same has traveled a given distance, an armature connected with said terminal, magnetic means for attracting said armature to change the position of the terminal with respect to the plunger so that an electrical connection is maintained during the entire return stroke of the plunger, a circuit closed by the electrical connection between the terminal and the plunger, a marker thrown into operation by the closure of said circuit, a shunt circuit for energizing the magnetic means, and means connected with the loud pedal for throwing the full current through the shunt circuit for the purpose of changing position of the terminal, substantially as described.

5. A recording attachment for a piano, having in combination, a plunger adapted to be actuated by the key, a terminal located to be contacted by the plunger when the same has traveled a given distance, a circuit completed by such contact, a marker put into operation by the completion of said circuit, a shunt circuit including magnetic means for changing the position of the terminal so that it remains in contact with the plunger during the entire return stroke and means connected with the loud pedal for throwing the full current through the shunt circuit, substantially as described.

6. A recording attachment for a piano, having in combination, a plunger adapted to be actuated by the key, a terminal adapted to be contacted by the plunger when it has traveled a given distance, a circuit closed by the contact of plunger and terminal, a marker put into operation by the closure of said circuit, means for changing the position of the terminal so that it remains in contact with the plunger during the entire return stroke and means for initially interrupting said circuit each time the key is depressed, but before the plunger contacts the terminal if the means for changing the position of the terminal is not in operation, substantially as described.

7. A recording attachment for a piano, having in combination, a plunger adapted to be actuated by the key, a terminal ar-

ranged to be contacted by the plunger when the same has traveled a given distance, a circuit closed by said contact, a printer put into operation by such closure of the circuit, means for changing the position of the terminal so that the circuit remains closed during the entire return stroke of the plunger, the said circuit containing an interrupter device and a pawl or trip on the plunger for operating the interrupter device, substantially as described.

8. A recording attachment for a piano, having in combination, a plunger adapted to be actuated by the key, means for completing a circuit upon the travel of the key a given distance, the said circuit, a marker, means for throwing the marker into operation upon the completion of the circuit and means operated by the loud pedal for prolonging the closure of the circuit upon the return stroke of the said plunger, substantially as described.

9. The combination with a musical instrument, provided with a loud pedal, of a recording attachment comprising a plunger adapted to be actuated by the key, a circuit completed by the travel of the plunger a given distance, a marker thrown into operation by the completion of said circuit, means for prolonging the closure of said circuit upon the return stroke of the plunger, and interrupter means operable when the loud pedal is on for temporarily interrupting the said circuit to indicate separate taps on the same key, substantially as described.

10. The combination with a musical instrument, provided with a loud pedal, of a recording attachment comprising a plunger adapted to be actuated by the key, a circuit closed by the plunger when the same has traveled a given distance, a marker thrown into operation by the closure of the circuit, and means for prolonging the closure of the circuit upon the return-stroke of the plunger, comprising a terminal, an armature connected therewith, a magnetic coil for attracting the armature and changing the position of the terminal with respect to the plunger, a shunt circuit including said coil and connected with said first mentioned circuit, and a make-and-break device, for breaking the said circuit when the loud pedal is depressed and thereby throwing the full current through the shunt circuit, substantially as described.

11. A recording attachment for a piano, having in combination, a plunger adapted to be actuated by the key, a circuit completed by the travel of the plunger a given distance, a marker thrown into operation by the closure of said circuit, means for prolonging the closure of the circuit upon the return stroke of the plunger, and interrupter mechanism for temporarily interrupting

the circuit to show separate taps upon the key when the means for prolonging the closure of the circuit is on, said interrupter mechanism comprising a pair of terminals, 5 an interrupter bar included in said first mentioned circuit, and a spring-operated pawl on said plunger adapted to temporarily trip the interrupter bar upon the

down stroke of the plunger, substantially as described.

In testimony whereof, I sign this specification in the presence of two witnesses.

GEORGE N. GOODRICH.
